FOLDABLE BED

Teodoro Basas Bardají, Barcelona, Spain, assignor to Jose Maria Bragulat, New York, N. Y.

Application November 22, 1934, Serial No. 754,237
In Spain December 7, 1933

7 Claims. (Cl. 5—69)

This invention relates to foldable beds, and has for its object to provide an improved device which is applicable to foldable beds in which the part corresponding to the head of the bed and, in some cases, also the foot part can be raised. By means of this device the result is obtained that the movement of raising the head of the bed and the foot part can be effected with the minimum of effort and with great simplicity, and also that the person lying in the hinged bed is able to regulate it to the desired inclination without the help of another person.

Foldable beds as described above are already known per se, and are employed mainly by invalids and convalescents for whom a more comfortable rest is desirable. These beds, in the normal position, have the appearance of an ordinary or plain bed, but, if the invalid has to be raised on it, the metallic bed bottom or spring or box mattress is hinged up for the head part and for the foot part as required until the desired position is obtained.

Nevertheless, all the hitherto known systems of beds of this class have the important disadvantage of requiring for their movement a great effort or else a mechanism which is complicated, expensive and slow in operation and cannot be worked by the person lying in the bed. The arrangements usually adopted comprise racks, worms or toothed sectors, and their mechanisms are actuated by means of handles or pulleys.

The device forming the subject matter of this invention enables a portion of the bed spring to be folded or moved on a pivot as already stated, without any effort and rapidly and without the aid of another person. Moreover, it is of great simplicity and therefore economical.

In order that the invention may be clearly understood reference will now be made to the accompanying drawing which illustrates a practical embodiment of the invention solely by way of example.

Fig. 1 is a side elevation of the device applied to a hinged bed, the bed being shown in the normal or extended position.

Fig. 2 is a view in elevation of the parts shown in Figure 1 as they appear from the opposite side.

Fig. 3 illustrates the same device, in an external side-view similar to Fig. 1, but with the head portion and the foot portion of the bed spring raised.

Fig. 4 shows diagrammatically the combination of a bed with a device installed thereon in the condition shown in Fig. 1.

Fig. 5 illustrates a bed with the device in the condition shown in Fig. 3.

The device, in the embodiment of the invention shown in the drawing, comprises a system of springs 1—2 which can be joined together in pairs, threes or more, as required, and these springs are fastened at both ends to the frame of the spring 3 and, at their center to a connecting rod 4. The connecting rod is floating in the sense that its lower end is not mechanically fixed in any predetermined position but depends for its position entirely upon the tension springs by which it is supported.

This connecting rod 4 is hinged at 5 to the frame of the movable part of the head 6 of the bed to which it transmits a thrust which it receives from the springs 1 and 2. Preferably the connecting rod is not pivoted directly to the head portion 6 of the spring frame, but is pivotally secured to a short arm 5' which may desirably have a length approximately equal to the spacing between the arm 5' and the fulcrum pin 7 upon which the head frame portion 6 is angularly adjustable. By virtue of the tension of these springs, the connecting rod 4 tends to maintain itself in the raised position (see Fig. 3) and thus, in turn, effects the raising of the head 6 of the bed spring. The advantage of employing the short arm 5' to locate the pivot 5 below the level of frame 6 is to maintain a sufficient leverage on the frame in the lifting movement thereof. Obviously, if the fulcrum 5 were located directly on the side of the movable frame section 6, the leverage of the connecting rod on such frame section would rapidly decrease as the frame section became elevated. By the arrangement disclosed, a substantially constant leverage is maintained sufficient in view of the decreasing load of the occupant's body on this frame section, to maintain the frame section upright notwithstanding the decreased tension of the counterbalancing springs resulting from their contraction.

As the tension given to the spring 1—2 (which can be regulated by means of spreaders 8) is calculated so as to counteract the weight of the person lying in the bed, any movement of the latter would cause a rocking of the head of the bed and, on the other hand, when the bed is unoccupied, the latter would always remain with the head portion raised. In order to avoid this disadvantage and to be able to leave the spring frame fixed in the desired position, there has been provided a sector 9 joined at one part to the head of the bed and passing through a guide 10 within which it can be immovably secured by means of a screw 11.

If desired, the foot part 12, 12' can also be pivotally arranged, so as to be capable of being folded in conjunction with the head of the bed (by means of a connecting rod device 13) or independently of the latter. The connecting rod 13 is preferably pivoted to the head section 6 of the spring frame at the end of a short lever arm 15 which projects from the pivoted end of the head frame 6. The connection of the link or rod 13 with the foot frame element 12 is effected through a short lever arm 16 which projects from the pivoted end of the foot section 12 in a direction opposite to that in which arm 15 projects. Thus, in this preferred arrangement of the parts, the upward movement of the head frame member 6 is accompanied by an opposite upswing movement of the foot member 12 which rests beneath the upper legs and knees of the occupant and which draws up with it the pivoted foot section 12' beneath the lower legs of the occupant.

In the former case, as is shown in the example of embodiment represented in the drawing, the actual device for counterbalancing the head part of the spring frame will serve for balancing or counteracting the weight of the foot part, and in the case in which the folding of the latter part is effected independently of that of the head part, there can be separately arranged a similar counterbalancing device which acts solely for the foot part.

From what has been set forth above, the operation of the described device can be clearly deduced; this consists in counteracting the weight of the hinged part of the bed bottom and that of the person whom it supports by means of a system of springs which exert a tension in a suitable direction tending to maintain the hinged part of the bed bottom in the raised position.

The disclosed arrangement whereby the head portion 6 of the bed spring frame and the lower portions 12 and 12' thereof are interconnected for simultaneous upward movement under the pressure of the counterbalancing spring system is very desirable in facilitating the almost effortless self-adjustment of the bed at the will of the occupant. Of course, the counterbalancing springs are so fixed that even the slightest lifting of the occupant's body will permit the bed spring frame sections to be raised by the springs. If, however, the occupant be a patient so weak as to be unable to lift his body alone, he can accomplish the elevation of the bed spring frame sections by simply drawing up his knees. This natural movement of the occupant's body conforms to the movement of parts 12 and 12' from the Figure 4 position to the Figure 5 position thereof and the release of the pivotal joined foot parts 12 and 12' from the load of the patient's knees is in itself sufficient to raise not only the foot sections 12 and 12' but the head section 6 of the bed spring frame. Conversely, a slight straightening of the occupant's body sufficient to supplement the weight of the knees on the joint between the foot sections 12 and 12' is sufficient to restore the parts to their Figure 4 position. Thus the counterbalancing springs do not need to be accurately adjusted to the weight of the occupant's body and, throughout a wide range of body weights, the bed spring frame sections respond so readily to the occupant's wishes as to make the operation seem completely effortless.

The device is advantageously mounted on both sides of the frame of the bed for the sake of better efficiency, but it may also be arranged on one only of its sides.

It should be noted that the counterbalancing device described may be subjected to accessory modifications, alterations and changes which do not affect its essence.

What I claim is:

1. A foldable bed, comprising the combination with a bed frame and a pair of bed spring sections having their adjacent end portions individually pivoted to the bed frame, of an arm extending downwardly on one of said portions, an arm extending upwardly on the other of said portions, a link connecting said arms for the elevation of one portion upon the elevation of the other, and counterbalancing means applied between one of said portions and the bed frame in a direction tending to elevate both of said bed spring portions in opposite angular directions.

2. A foldable bed, comprising the combination with a bed frame, of three movable bed spring sections, the first of which has its foot end pivoted to an intermediate portion of the bed frame,

25 the second of which has its head end pivoted to an intermediate portion of the bed frame, and the third of which is pivotally connected to the foot end of the second, positively acting means connecting the first and second sections whereby any upward or downward movement of either section produces a corresponding upward or downward movement of the other section, the 30 third section likewise participating in said movement to swing upwardly and downwardly in correspondence with the upward and downward movement of said first and second sections, and a counterbalancing spring applied between said bed frame and at least one of said sections for supporting all three of said sections in their upward movement, said spring having sufficient tension to substantially balance the weight of the moving portions of said sections and the 35 weight of the portions of an occupant's body resting thereon, whereby an occupant of the bed spring can substantially effortlessly raise and lower his knee and trunk simultaneously in opposite directions of pivotal movement by shifting the direction of thrust of portions of his legs upon the second and third sections aforesaid.

45 3. A foldable bed comprising the combination with a main frame, of an adjustable sub-frame 50 comprising a first section having its foot in fulcrumed connection with an intermediate part of the main frame, a second section having its head in fulcrumed connection with an intermediate part of the main frame and a third section pivotally connected to the foot end of the second section, arms respectively extending upwardly and downwardly on the first and second sections, a link connecting said arms whereby the upward movement of one of said sections will occasion 55 the upward swinging movement of the other, and a counterbalancing spring of substantially sufficient strength to support the free end portions of said sections and the body of the occupant thereon in the course of the swinging movement aforesaid, said spring being operatively connected between said main frame and at least one of the said sections.

4. A foldable bed comprising the combination with a main frame, of an adjustable sub-frame 70 comprising a first section having its foot in fulcrumed connection with an intermediate part of the main frame, a second section having its head in fulcrumed connection with an intermediate part of the main frame and a third section piv- 75

totally connected to the foot end of the second section, arms respectively extending upwardly and downwardly on the first and second sections, a link connecting said arms whereby the upward movement of one of said sections will occasion the upward swinging movement of the other, a link and pivotal connection with one of said sections and depending below said main frame at its free end, and a counterbalancing spring system having its intermediate portion secured to the depending free end of said link and its ends connected with said main frame under tension for the support of the several sections and the weight of a person's body in the swinging angular adjustment of said sections.

5. A foldable bed comprising the combination with a bed frame, of three movable frame sections the first of which has an end portion adjacent the head of the bed free to swing in an upward direction and has its foot section provided with means supported on said bed frame and providing a relatively fixed fulcrum for pivoting it at a point intermediate the ends of the bed frame, the second of which has its head end provided with means pivoting it adjacent the point at which the foot end of the first section is pivoted, the foot end of the second section being free to swing in an upward direction, and the third of which is pivotally connected at its head to the foot end of the second, its foot end being provided with means supported from the bed frame for the pivotal movement of said third section in response to the movement of the second, positively acting means connecting the first and second sections whereby any upward or downward movement of either section produces a corresponding upward or downward movement of the other section, the third section likewise participating in said movement to swing upwardly and downwardly in correspondence with the upward and downward movement of said first and second sections, and a counterbalancing spring applied between the bed frame and at least one of said positively connected sections in a direction to support all three of said sections and to contribute to the support of the portions of the occupant's body which rest upon the free end portions of the several sections, the several sections being movable from a position of substantial alignment to positions in which the swinging portions thereof are entirely above the first mentioned position, the tension of said counterbalancing spring being of such a value that the occupant can effect the movement of the several sections substantially without effort by shifting the relative direction of thrust of the several portions of his body upon the several sections.

6. An adjustable bed comprising the combination with a bed frame, of a bed spring including a

head section, an intermediate section, and a foot section, means providing relatively fixed fulcrums for the adjacent end portions of the head section and the intermediate section upon the main frame, means providing a pivotal connection between the free end of the intermediate section and the adjacent end of the foot section, the free end of the foot section being movable along the main frame, positively acting means operatively connecting said head section and intermediate section to require opposite angular movement about their respective pivot means in corresponding upward and downward directions, whereby the head and knee portions of an occupant of the bed spring will be raised and lowered simultaneously, the movement of the various sections ranging from a position of substantial horizontal alignment to other positions in which the movable portions of the respective frames are wholly above said first mentioned position, and means for resiliently acting upon at least one of said frames for urging the several frames toward said last mentioned positions, said resiliently acting means being sufficient to counterbalance substantially the weight of the moving parts of the frame and the portions of an occupant's body carried thereby, whereby an occupant can vary his position without material effort by straightening and bending his body to lower and raise the movable portions of said sections respectively.

7. A foldable bed comprising the combination with a bed frame, of a bed spring consisting of a head section, an intermediate section and a foot section, means mounted on the main frame providing for the independent support of adjacent ends of the head and intermediate sections for pivotal movement, positively acting mechanism operatively connecting said sections for the transmission of motion from one to the other in a direction to require said sections to pivot angularly in opposite directions upon the movement of either of said first and second sections, whereby to cause the simultaneous movement of the head and knee portions of an occupant in an upward direction or a downward direction, the adjacent ends of the intermediate section and foot section being provided with means establishing a pivotal connection therebetween, and spring actuating means acting upwardly on one of the sections connected by said mechanism in a direction to substantially counterbalance the swinging portions of said sections and the portions of the weight of an occupant supported thereon, whereby a change in the direction of thrust of portions of the operator's legs on the intermediate and foot sections will effect substantially effortless raising and lowering of the several sections.
